(57) **CLAIM**

The ornamental design for a food serving plate, as shown and described.

DESCRIPTION

FIG. 1 illustrates a top plan view of a food serving plate showing our new design;

FIG. 2 is a side perspective view of the plate of FIG. 1; FIG. 3 is a side elevation, the side opposite being a mirror image; and,

FIG. 4 is a bottom plan view thereof.

The broken lines shown in FIG. 4 define the bounds of the claimed design and form no part thereof.
